Attorney*

UNITED STATES PATENT OFFICE.

JOSEPH A. KLESLER, OF ST. JOHNS, OREGON.

PLUMB-BOB.

1,286,023.

Specification of Letters Patent.

Patented Nov. 26, 1918.

Application filed January 22, 1917. Serial No. 143,654.

To all whom it may concern:

Be it known that I, JOSEPH A. KLESLER, a citizen of the United States of America, residing at St. Johns, in the county of 5 Multnomah, in the State of Oregon, have invented certain new and useful Improvements in Plumb-Bobs, of which the following is a specification, reference being had to the accompanying drawing.

10 My invention relates to plumb bobs, and has for its object the production of a device in which improved mechanism for winding a suspension cord within a bob is provided. The ordinary plumb bob is, in 15 practice, attached to the lower end of a suspension cord and its length is adjusted from the upper end. This is objectionable because of the time and consequent expense involved whenever the cord is of any considerable length, for the reason that it requires either manipulation by two persons, or the repeated attentions of one person to the opposite ends, alternately, of the cord.

With the view of overcoming this difficulty, plumb bobs provided with mechanism for automatically winding the suspension cord within the bob have been devised. Such mechanism, however, fails to overcome the objection for the reason that 20 it is expensive to manufacture, liable to get out of order, and dependent for its operation upon the presence of a spring in its mechanism.

By the aid of my invention a plumb bob 25 is made adjustable to a nicety from the lower end of a suspension cord where it may, without the use of a winding spring, be positively adjusted so as to shorten or lengthen the cord at will.

40 What constitutes my invention will be hereinafter specified in detail and succinctly set forth in the appended claims.

In the accompanying drawing,

Figure I is a side elevation, partially in 45 section, of my device in preferred form of embodiment, shown depending as in use, from its suspension cord.

Fig. II is a view similar to Fig. I, but with less of the interior mechanism exposed, and showing members of the train of gear disconnected in order to permit freedom of movement to the cord, and thereby rapid descent of the bob to any point of accurate adjustment desired.

55 Fig. III is a top plan view of the sup-

porting disk for the actuating head of the winding drum of my bob, detached.

Fig. IV is a side elevation of the inside supporting frame and its cap detached from the case within which it is shown in Fig. I, 60 the view in Fig. IV being taken at right angles to that in which it is shown in Fig. I.

Referring to the numerals on the drawing, 1 indicates a plumb bob proper which may be of any preferred weight, dimensions and 65 exterior contour. It is provided in its upper end with a preferably cylindrical cavity 2 whose upper end is preferably provided with internal screw threads 3 to receive corresponding threads of a neck 4 projecting 70 from the inner side of a cap 5.

A frame comprising a pair of legs 6 is provided in conjunction with the cap 5 from the inner side whereof it projects, preferably integrally with it and its neck 4. 75

The legs 6 extend nearly to the bottom of the cavity 2, and are, equidistantly from each other, spaced to accommodate between them a drum 7, rotatably mounted upon an arbor 8, which, being preferably inserted 80 through an aperture in one leg, has its further extremity screwed into a threaded aperture provided for it in the other leg.

The drum is provided, preferably at one end, with a gear 10, which meshes with an 85 idler 11, secured by a headed stud-shaft 12 to the leg adjacent to the gear 10.

The idler 11 is in train with the gear 10 through a spur gear 14. It is also provided with a bevel gear 15 adapted to intermesh 90 with a bevel gear 16.

The gear 16 is coaxially threaded to a tubular shaft 17 that is provided on its outer end with a preferably integral actuating head 18. 95

Between the gear 16 and the cap 5 is interposed an expansive coiled spring 19 which is preferably let into a cavity 20 provided for it in the inner face of the cap 5 and its neck 4. The function of the spring 100 19 is to compel normal engagement between the bevel gears 16 and 15 through thrust imparted to the shaft 17, and at the same time to seat the head 18 against a disk collar 21 surrounding the shaft 17 and interposed between the head 18 and the outer face of the cap 5. During engagement between the bevel gears 16 and 15 the collar 21 and head 18 are in effect unified by engagement of pins 22 projecting from the inner face of the 110

head 18 into engagement with sockets 23 provided for their reception, respectively, in the collar 21. The outer peripheries of the collar and head are preferably knurled to facilitate their joint or independent rotation.

If the spring 19 be compressed sufficiently to permit disengagement of the pins 22 from their sockets 23, and consequently the independent rotation of the head 18 and collar 21, the head may be, by such independent rotation sufficient to effect disalignment of the pins and their sockets, supported in the position shown in Fig. II. So long as they continue in that relative position last mentioned, the gear 16 is disengaged from the gear 15 and the drum 7 is thereby permitted to run free of connection with the gear 16.

25 indicates a suspension cord which is threaded through the bore of the tubular shaft 21 and through an aperture in the head 18 coaxial therewith. Its inner end is secured to the drum 7 in any suitable manner so as to compel it to wind and unwind thereon and therefrom upon rotation of the drum.

The operation of my device may be briefly described as follows:

The parts of the apparatus being assembled as shown in Fig. I, and the cord 25 dropped in the usual manner from a point of support and its upper end, the bob may be raised and lowered at will by rotating the head 18 in one direction or the other. The rotation of the head imparts, through the idler 11 and the gear 10, rotation to the drum 7, thereby effecting adjustment of the length of the cord. Such manipulation of the head 18 as that last described is for the purpose of comparatively fine adjustment 40 of the length of the cord 25. Whenever it is desired to pay out a considerable length of cord, the head 18 is adjusted to the relative position shown in Fig. II, wherein a pull upon the bob proper will permit the free rotation of the drum 7 and the rapid unwinding of the cord 25.

When the gears 16 and 15 are in engagement with each other they constitute, in respect to the drum 7, parts of an effective brake mechanism sufficient to prevent unwinding movement of the drum 7 under tension upon the cord 25. The effect thereof is to lock the cord to the plumb bob, to all intents and purposes, as if they were fixedly united as in the common bob.

It may be mentioned, as one of the conveniences incident to the construction of my device, that the cord 25 may be kept wound upon the drum 7, except when it is drawn out for the suspension of the bob in service.

What I claim is:

1. A plumb bob comprising a drum revolvably mounted within it, means for passing a suspension cord through the upper end of the bob into operative connection

with the drum, means permanently secured upon the outside of the bob in operative connection with the drum adapted to rotate the drum in opposite directions, and means for disconnecting the drum and the means for 70 operating it whereby the drum may be rotated in one direction by a pull upon the suspension cord attached to it.

2. The combination with a plumb bob proper provided with a cavity, of a frame 75 adapted to enter the cavity, said frame being provided with a rotatable drum adapted to be connected to one end of a suspension cord, means for passing the suspension cord through the frame, means for actuating the drum from the outside of the assembled bob and frame, said last named means comprising a train of gears on the inside of the frame and an actuating member on the outside thereof, and means for uniting the bob 80 and frame.

3. The combination with a plumb bob proper provided with a cavity, of a frame 85 adapted to enter the cavity, said frame being provided with a rotatable drum adapted to 90 be connected to one end of a suspension cord, means for passing the suspension cord through the frame, means for actuating the drum from the outside of the assembled bob and frame, said last named means comprising a train of gears on the inside of the frame and an actuating member on the outside thereof, outside means for disconnecting 95 the train of gears and the actuating member, and means for uniting the bob and 100 frame.

4. The combination with a plumb bob proper provided with a cavity, of a frame insertible and securable within the cavity, a pair of legs on the inner end of the frame, 105 a drum revolvably mounted between the legs, a gear secured to the drum, a spring pressed tubular shaft extending through the frame, a gear secured to said shaft, an idler mounted on the inside of the frame and adapted 110 operatively to connect both the gears named, and outside means for actuating the shaft in both directions thereby actuating the drum.

5. The combination with a plumb bob 115 proper provided with a cavity, of a frame insertible and securable within the cavity, a pair of legs on the inner end of the frame, a drum revolvably mounted between the legs, a gear secured to the drum, a spring pressed 120 tubular shaft, a gear secured to said shaft, an idler mounted on the inside of the frame and adapted operatively to connect both the gears named, outside means for actuating the shaft in both directions thereby actuating 125 the drum, and outside means for connecting and disconnecting the tubular shaft and the drum.

6. The combination with a plumb bob proper provided with a cavity, of a frame 130

insertible and securable within the cavity, a pair of legs on the inner end of the frame, a drum revolvably mounted between the legs, a gear secured to the drum, a spring pressed tubular shaft, a gear secured to said shaft, an idler mounted on the inside of the frame and adapted operatively to connect both the gears named, outside means for actuating the shaft in both directions thereby actuating the drum, and outside means for connecting and disconnecting the tubular shaft and the drum, said last named means consisting of a head perforated coaxially with the

tubular shaft for accommodation of a suspension cord, a collar surrounding the shaft 15 between the frame and the head, and means for keeping the head and collar separated upon rotation of the head or collar independently.

In testimony whereof, I have hereunto set 20 my hand in the presence of two subscribing witnesses.

JOSEPH A. KLESLER.
